[57] CLAIM

The ornamental design for an analytical balance, as shown.

DESCRIPTION

FIG. 1 is a top, front, and left side perspective view of the analytical balance showing our new design in a closed position in FIGS. 1-5;

FIG. 2 is a right side elevational view;

FIG. 3 is a top plan view;

FIG. 4 is a front elevational view;

FIG. 5 is a rear elevational view;

FIG. 6 is a top, front, and left side perspective view in an open position in FIGS. 6-8;

FIG. 7 is a right side elevational view; and

FIG. 8 is a top plan view thereof.
